Primary Examiner — Vy N Koenig*(74) Attorney, Agent, or Firm* — The Law Offices of Konrad Sherinian LLC(57) **CLAIM**

The ornamental design of a blank for an article organizer, as shown and described.

DESCRIPTION

FIG. 1 is a top plan view of a blank for an article organizer showing my new design, the bottom being a mirror image thereof;

FIG. 2 is a top plan view of another embodiment of a blank for an article organizer showing my new design, the bottom being a mirror image thereof; and,

FIG. 3 is a top plan view of a third embodiment of a blank for an article organizer showing my new design, the bottom being a mirror image thereof.

The broken lines shown are directed to environment for purposes of illustration and form no part of the claimed design.
